UNITED STATES PATENT OFFICE.

JOHN S. PADON, OF LEBANON, ILLINOIS.

FARM-GATE.

SPECIFICATION forming part of Letters Patent No. 223,944, dated January 27, 1880.

Application filed September 20, 1879.

To all whom it may concern:

Be it known that I, JOHN S. PADON, of Lebanon, in the county of St. Clair and State of Illinois, have invented certain new and useful 5 Improvements in Farm-Gates; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a side elevation of my gate, partly in section. Fig. 2 is an end view, and Fig. 3 is a 15 detail view.

My invention relates to a gate for farm purposes and the like; and the novelty consists in the construction and arrangement of parts, as will be more fully hereinafter set forth, and 20 pointed out specifically in the claim.

In carrying out my invention I employ proper revolving guides, which are journaled in the base or posts and support the gate. The gate operates between posts, which serve as guides 25 to prevent deviation from a direct plane motion. An upper roll serves to assist in preventing friction and in steadyng the motion of the gate. The upper rail of the gate has an under friction-surface or cog-bar, and engages with a 30 proper wheel operated by cranks upon either side of the fence. These cranks are loosely connected to the shaft of the operating-wheel, as shown. The cranks are journaled in posts or other supports upon each side of the fence, so 35 that the gate may be moved identically from either side. A pivoted arm upon the upper rail of the gate connects with a trigger rigid with the gate-latch, and a lug upon the rail prevents said arm from moving forward beyond a certain 40 limit. Studs or pins rigid upon the operating-wheel serve, when the wheel is revolved in one direction, to close the gate and lock the latch, and in the opposite direction to unlock the latch. A spring against the trigger serves 45 to hold the latch in locked position with a con-

stant force, and a lug operating upon a roller journaled in the latch-post serves to relieve the latch-connection from the weight of the gate.

Referring to the drawings, A represents the guide-posts, and A' the latch-post. The latch-lock a' is situated between the standards of the latch-post, and a roller, a², is journaled below the latch-lock, which operates to support the gate by means of a lug, b, having an inclined face, b', upon the gate B, as shown. 55

Journaled in the base-plate or in the guide-posts A are friction guide-rollers C, and a similar guide-roll, C', engages the upper rail of the gate B. This upper rail, D, of the gate B has its under surface provided with a friction-surface or rack-bar, B', which operates in connection with a wheel, E, having a periphery to correspond with the surface B'. Arms e upon the wheel E operate upon a pivoted arm, F, upon the rail D, to operate a trigger, G, through 60 a connection, g, as shown. The trigger is rigid with the latch H, and a spring, I, serves to hold the latch in a locked or depressed condition with a constant force.

The shaft of the wheel E is loosely connected 70 with crank-shafts J, journaled in posts K upon either side of the fence, as shown.

The operation of my invention is obvious.
What I claim is—

In a sliding or rolling gate, the combination 75 of the rail D, secured to the gate B, the wheel E, mounted upon a shaft and provided with arms e, and the pivoted arm F, connected by a wire, g, to the upper end of the trigger G, connected to the latch H, the whole being operated by the crank-rods J, as and for the purposes set forth. 80

In testimony that I claim the above I have hereunto subscribed my name in the presence of two witnesses.

JOHN S. PADON.
